UNITED STATES PATENT OFFICE.

JAMES BARKER, OF ANN ARBOR, MICHIGAN, ASSIGNOR TO THE TORMAN BASSETT COMPANY, A CORPORATION OF OHIO.

BANKING.

1,315,591.

Specification of Letters Patent. Patented Sept. 9, 1919.

Application filed March 29, 1919. Serial No. 286,046.

To all whom it may concern:

Be it known that I, JAMES BARKER, a citizen of the United States, residing in the city of Ann Arbor, State of Michigan, have invented certain new and useful Improvements in Banking, of which the following is a specification.

My invention relates particularly to a device for use in connection with partial payment plans of saving or of purchasing bonds or other securities. Government bonds are commonly sold through banking institutions on the partial payment plan by which a certain amount is to be paid periodically and when so paid to be credited toward the purchase of the bond. Many banking institutions have organized and operate so called Christmas clubs in which members agree to deposit throughout the year, or for a definite period, at regular intervals, a certain amount of money which is to be held by the banker until all the payments are made or the obligation matures at which time the bank is to pay to the depositor or club member a definite predetermined amount based on the payments made by the member. While not limited in its use to either of these schemes of operation, my invention is especially directed toward them.

To this end, my invention comprises, in the specific form in which I have developed it, a deposit book or a pass book. The book has the usual, or any desirable, cover and includes between the covers numerous sheets, some of which are perforated and detachable and some of which are perforated for detachment in sections.

I may place upon the cover advertising matter relating to the particular bank which is to receive the deposits and some indication of the character and type of the transaction to be conducted together with such rules and explanations as may be necessary or desirable.

One of the sheets of the book preferably consists of a bond or cashier's check or other arrangement to make the required payment to the purchaser or to deliver the bond to the purchaser which is to be signed and become valid on the completion of the partial payments or at some specified date. Preferably the reverse side of this sheet contains space for indorsement on payment and also space for registering the name and address of the purchaser or club member in such a

position that such name and address alone will be visible when the sheet is placed in a "window envelop". The arrangement is preferably such that the cover may be folded back and the whole book placed in an envelop so that the name and address will appear through the window. I prefer to make the book of a size suitable to be inclosed within a standard sized envelop but of course it may be made of any size and associated with a corresponding envelop. Preferably this sheet is perforated for ready detachment from the book after the other sheets have served their purpose as hereinafter described.

Another sheet in my book preferably consists of two portions and is perforated so that each portion may be separated from the other and from the rest of the book. One of these separable portions preferably consists of a standard signature card of the type commonly used by banks for receiving and recording the signature and address of a depositor. The other portion of this sheet preferably consists of a card or slip to be delivered to the auditor or other suitable officer of the bank to indicate that this particular account has been opened and payment in accordance with the requirements of the book may be expected. The bond sheet above described carries on it a serial number and the same serial number appears on the auditor's slip and on the signature card as well as on each of the detachable coupons on the other sheets now about to be described.

In order to conveniently provide for and accommodate the partial payments called for by the scheme of banking contemplated by my invention I provide other sheets in my book. These other sheets preferably consist of two kinds and are preferably bound in alternately. One set of sheets consists of a plurality of coupons perforated for detachment from each other and from the book, each bearing the identifying number of the account and serially numbered beginning with 1. I provide one such coupon for each of the partial payments contemplated by the particular scheme to which the particular embodiment of my invention is adapted. Preferably each coupon also carries on it some date or other indication of the time when the partial payment represented by the coupon should be made as contemplated by the particular scheme in which the book

is to be used. Each sheet is made up of a number of such coupons and is preferably succeeded by an imperforate sheet bearing numbers corresponding to the serial numbers of the detachable coupons on the adjoining sheet and providing in association with such numbers a space on which may be marked the teller's receipt for the payment indicated or demanded by the corresponding detachable coupons. I prefer to make these imperforate sheets bearing the receipts narrower than the coupon sheets associated with them.

While my invention is adapted for other uses I will describe it as applied to a Christmas club partial payment scheme calling for weekly payments of one dollar resulting in a return by the bank of fifty dollars to the depositor or club member but my claims are not to be so limited.

I have shown one form of my book in the accompanying drawings in which Figure 1 is a perspective view of the book with some of the leaves exposed to view. Fig. 2 is a perspective view of the book folded so as to expose the reverse side of the bond sheet showing in dotted lines the inclosing envelop and the window therein. Fig. 3 is a plan view of the book opened to show the bond sheet and one sheet of detachable coupons, some of which have been detached to show the receipt sheet below. Fig. 4 is a plan view of the book opened to the sheet containing the signature card and the auditor's coupon.

My book may have a cover A inclosing the various pages. I have not shown the cover in detail but it will be understood that it may carry the usual printed matter indicating the character of the transaction for which the book is to be used and also the name of the bank issuing the book as well as space for the name of the depositor or purchaser and rules relating to the particular scheme with which the book is to be used and any other desired matter.

Preferably the first sheet B in the book is the bond sheet, the face of which is shown in Fig. 3 and the reverse of which is shown in Fig. 2. The relative position of this and the other sheets in the book is not essential and the arrangement I have shown is merely for purposes of illustration. As shown the bond is for fifty dollars but it might be for any other amount or call for a Government bond or anything else depending on the scheme of operation or the partial payments. The last sheet C in the book I prefer to provide with the address card D and the auditor's coupon E as illustrated in Fig. 4. The intermediate sheets are made up of two kinds. The sheets F being the coupon sheets as illustrated in detail in the lower right hand part of Fig. 3. Alternating with these sheets are the receipt sheets G shown in de-

tail in the upper right hand part of Fig. 3. These sheets are shown as used in a scheme calling for the payment of one dollar each week but with suitable obvious changes they might be adapted to any other scheme calling for any other payments at the same or suitable other intervals or times.

In practice these books will be kept in the bank in regular order until they are to be used. When a person wishes to become a member of the savings club, a book is presented to him. From the drawings it will be noted that the bond, the signature card, the auditor's coupon and the detachable coupons all carry the same number, 1275. It is to be assumed that there have already been opened 1274 accounts. When the 1275th customer approaches, he will be asked to place his signature and address on the signature card D and it will be detached at the perforations indicated in Fig. 3 and retained for filing. At the same time the teller will stamp and detach the auditor's coupon E which will be handed either immediately or at the end of the day's business or periodically to the auditor or some other official of the bank to indicate that the account represented by the serial number 1275 has been opened. Some cashiers like to have this information at hand where the bank does not have business enough to keep their regular auditor. The teller will then remove the detachable coupon numbered 1 on the sheet F. It will be noted that in Fig. 3 the coupons numbered 1, 2 and 3 have already been removed. This coupon will be retained by the receiving teller in lieu of a deposit slip and subsequently handed to the bookkeeper or proper official for record or entry.

At the same time the teller may stamp on the receipt sheet G the date and his number in the space near the No. 1 on the sheet. The teller may then write the name and address of the purchaser on the reverse side of the bond sheet B as indicated in Fig. 2. It will be noted that the lines for this name and address are so placed on the reverse side of the sheet B that when the name and address is put upon them and the cover folded back the book may be placed in a window envelop H so that the name will show through the window I indicated by dotted lines in Fig. 2. Subsequent payments will be handled in connection with my book by the teller lifting the coupons as paid and putting his receipt stamp on the receipt sheet G adjacent the number corresponding to the coupon lifted. In Fig. 3 I have illustrated the condition after two such receipts have been indicated and while payment of coupon 3 is being made. Coupon 3 has been lifted or detached preparatory to placing the teller's receipt stamp on sheet G corresponding to coupon 3. For convenience of handling and ready distinc-

tion I have made the receipt sheets G narrower than the coupon sheets F so that they do not extend to the extreme margin of the book.

5 In order that the purchaser or member of such a club may keep up the partial payments, some incentive is desirable and I have provided this by putting in each book so that it will face the receipt sheets 10 and the coupon next due the bond representing the amount the bank will pay to the purchaser or club member at maturity so that the purchaser may constantly have before him the total sum he will receive 15 on completion of his contract for the partial payments. This bond forming one of the leaves of the book is also an additional convenience for the bank. It bears the same serial number as the coupons and the other 20 parts of the book and on payment of the last partial payment due under the scheme the cashier or other officer or the bank may detach this bond on the perforation shown. After verifying from the bank record that 25 the payments have been completed the bond may be signed by the cashier or other official of the bank and placed in a window envelop and mailed or otherwise delivered to the purchaser and act as a draft or 30 cashier's check on the bank for the amount due at maturity.

I claim as my invention:

1. A deposit book for use in partial payment plans comprising a sheet carrying a detachable portion adapted to receive the signature and address of the depositor and a detachable portion for the auditor, a sheet containing a statement of the value of the total of the partial payments to be signed by a 35 bank official when the partial payments are all made, alternate intermediate sheets containing a plurality of detachable coupons bearing a date, amount and serial number, alternate intermediate sheets bearing serial 40

numbers and adapted to receive marks 45 showing receipts of partial payments corresponding to the coupons, and a similar identifying number on each of the separable parts of the book.

2. A deposit book for use in partial payment plans comprising a sheet carrying a detachable portion adapted to receive the signature and address of the depositor, a sheet containing a statement of the value of the total of the partial payments to be 50 signed by a bank official when the partial payments are all made, alternate sheets containing a plurality of detachable coupons bearing a date, amount and serial number, alternate sheets bearing serial numbers and 55 adapted to receive marks showing receipts of partial payments, and a similar identifying number on each of the separable parts of the book.

3. A deposit book for use in partial payment plans comprising a sheet carrying a portion adapted to receive the signature and address of the depositor and a portion for the auditor, a sheet containing a statement of the value of the total of the partial pay- 60 65 ments to be signed by a bank official when the partial payments are all made, sheets showing amounts and due dates of the partial payments, sheets adapted to receive marks showing receipts of partial payments, 70 75 and a similar identifying number on each of the sheets.

4. A deposit book for use in partial payment plans comprising a sheet carrying a portion adapted to receive the signature 80 and address of the depositor and a portion for the auditor, sheets showing amounts and due dates of the partial payments, sheets adapted to receive marks showing receipts of partial payments, and a similar identi- 85 fying number on each of the sheets.

JAMES BARKER.

It is hereby certified that the assignee in Letters Patent No. 1,315,591, granted September 9, 1919, upon the application of James Barker, of Ann Arbor, Michigan, for an improvement in "Banking," was erroneously described and specified as "The Torman Bassett Company," whereas said assignee should have been described and specified as *The Forman Bassett Company*, as shown by the records of assignments in this office; and that the said Letters Patent should be read with this correction therein that the same may conform to the record of the case in the Patent Office.

Signed and sealed this 7th day of October, A. D., 1919.
